W. REENSTROM.

VENTILATOR.

APPLICATION FILED MAY 31, 1917.

1,424,944.

Patented Aug. 8, 1922.

UNITED STATES PATENT OFFICE.

WALTER REENSTROM, OF CHICAGO, ILLINOIS.

VENTILATOR.

1,424,944.

Specification of Letters Patent. Patented Aug. 8, 1922.

Application filed May 31, 1917. Serial No. 172,016.

To all whom it may concern:

Be it known that I, WALTER REENSTROM, a citizen of the United States, and a resident of the city of Chicago, county of Cook, and 5 State of Illinois, have invented certain new and useful Improvements in Ventilators, of which the following is a specification.

My invention relates to improvements in ventilators designed for use particularly 10 upon house tops, and has for its object the production of a device of this character which will be efficient in use and of durable and economical construction. A further object is the production of a process of manufacture 15 of a ventilator as mentioned whereby the same may be manufactured easily and economically, waste of material being reduced to a minimum. Other objects will appear hereinafter.

20 The invention consists in the combinations and arrangements of parts hereinafter described and claimed.

The invention will be best understood by reference to the accompanying drawings 25 forming a part of this specification, and in which,

Fig. 1 is a side elevation of a ventilator embodying the invention,

Fig. 2, a central vertical section of the 30 device,

Fig. 3, a top plan view of Fig. 1,

Fig. 4, a horizontal section through the device, and

Fig. 5, a top plan view of a sheet metal 35 blank illustrating the method of cutting of the same in the formation of the hood and aprons embodied in the ventilator.

The preferred form of construction as 40 illustrated in the drawings, comprises an outer tubular member consisting of a plurality of telescoping tubular sections 5. Said sections are rigidly connected at their points of overlapping by rivets 6. Arranged within said tubular member is a plurality of spaced longitudinally extending 45 reinforcing bars or straps 7 which are rigidly connected with the sections 5 by the before-mentioned rivets 6. The upper end portions of bars 7 are rigidly connected with the upper edge portion of the uppermost 50 section 5 by rivets 6'.

Arranged at and spaced directly over the upper end of said tubular member is a conical hood 8, the same being supported by the 55 upper ends of bars 7 which are extended upwardly in order to constitute supports

therefor. The hood 8 is formed of two semi-circular sections 8' and 8'', the edges of which are overlapped, said edges being notched to allow for said overlapping, as 60 clearly seen in Fig. 3. Said overlapping edge portions of said hood sections are rigidly secured together by rivets 9'.

Arranged at the upper edge of each section 5 is an annular downwardly and outwardly inclined apron 10 secured to said sections by means of the rivets 6 and 6'. Openings 11 are formed at the upper ends of each section 5 below the aprons 10 through notching or cutting away the upper 70 edge portions of said sections, as clearly seen in Fig. 2. The openings 11 do not extend below the lower edges of the aprons 10, this arrangement precluding a direct draft into said openings which would otherwise result, 75 did said openings extend below the lower edges of said aprons.

In the manufacture of the hood 8 and aprons 10, a rectangular flat blank of sheet metal is employed as seen in Fig. 5. Said 80 blank is cut along two spaced concentric lines 12 and 13, one-half of the hood being formed by the semi-circular portion within the line 12, and one-half of one of the aprons 10 being formed by the arcuate strip 10 between the lines 12 and 13. With this process or method of construction, only the corner portions 14 will be wasted. Concentrically arranged within the tubular member 5 of the ventilator is a smaller pipe 15 rigidly 85 held in position by means of arms 16. The upper end of pipe 15 is closed and provided with lateral openings 17. Said openings 17 are preferably arranged in substantially the same horizontal plane as the lowermost 90 openings 11. The tubular pipe surrounding the pipe 15 is prolonged at the lower end so as to allow both it and the pipe 15 to pass into and communicate with the interior of the building with which the device is used, 95 100 for ventilating purposes.

A ventilator of the construction set forth is extremely strong and durable and may be manufactured at a low cost. The peculiar arrangement of the various openings 105 and passages together with the arrangement of the pipe 15 insures the creation of a strong draft and hence thorough ventilation in connection with the building in which the ventilator is used.

While I have illustrated and described the preferred form of construction for carrying

my invention into effect, this is capable of variation and modification without departing from the spirit of the invention. I, therefore do not wish to be limited to the 5 precise details of construction set forth, but desire to avail myself of such variations and modifications as come within the scope of the appended claim.

Having described my invention what I 10 claim as new and desire to secure by Letters Patent is:

In a ventilator, the combination with a plurality of telescoping sections having their adjoining edge portions overlapping and secured together; longitudinally extending reinforcing bars connected to said sections, 15 the upper portions of said bars being ex-

tended beyond the upper edge of the upper section of said ventilator; a hood carried by and secured to said bars in spaced relation 20 with respect to the said upper section; angular downwardly and outwardly inclining aprons carried by and secured to the upper edge of each of said sections, and openings formed at the upper ends of each of said 25 sections, substantially as described.

In testimony whereof I have signed my name to this specification in the presence of two subscribing witnesses.

WALTER REENSTROM.
